CHUTE FEED, TIP GRATE INCINERATOR

Filed April 26, 1926

INVENTOR,
Joseph Feigenbaum,
BY G.E. Maynard,
ATTORNEY.

UNITED STATES PATENT OFFICE.

JOSEPH FEIGENBAUM, OF LOS ANGELES, CALIFORNIA, ASSIGNOR TO SAFETY CONCRETE INCINERATOR CO., INC., A CORPORATION OF CALIFORNIA.

CHUTE-FEED, TIP-GRADE INCINERATOR.

Application filed April 26, 1926. Serial No. 104,688.

This invention relates to domestic and industrial incinerators for burning waste and rubbish.

An object of the invention is to provide a novel type of spark arrester.

Another object is to provide a novel arrangement of feed chute in a forwardly offset relation to the front of the combustion chamber for the facile introduction of the material to be burned.

A further object is to provide a tipping grate mechanism, and to provide a liftable cover for the chute and having an operating connection with grate mechanism, where-
15 by when the grate is tipped, the cover will open for inspection of the fire chamber. And an object is to provide for the disconnection of the cover, at will, from the grate so that the former can be operated inde-
20 pendently of the latter, for introduction of rubbish.

An additional object is to provide a pneumatic check device for the falling cover.

Other objects and advantages will be made manifest in the ensuing specification of the herewith illustrated apparatus embodying the improvements; it being understood that modifications, variations and adaptations may be resorted to within the spirit and scope of the invention as claimed.

Figure 1 is a central, vertical section of the incinerator.

Figure 2 is a front elevation, partially in section.

Figure 3 is a detail side view of the grate and cover operating means.

Figure 4 shows a modified arrangement of the cover check.

The present incinerator is built of a series 40 of co-related, unitary sections of a suitable cementitious, concrete composition, preferably of a good fire resistant mixture.

A grate base 2 of suitable plan has a front opening 3 for air inlet and for extraction of 45 ashes and unburned residue. Seated in notches 4 at opposite sides of the grate base 2 are trunnions 5 and 6, the latter having a round shaft part and an outer square part 7 terminating in a head 8. The trunnion 6 is detachable from its side of a grate 10 having trunnion 4 at its opposite side. The grate conforms to the plan of the base 2 and has its trunnions forward of a diameter so that the rear end of the grate is heavier and 55 automatically falls to horizontal position.

The shorter front of the grate allows it to be tilted to a high angle to discharge débris, toward the opening 3 of the base.

The trunnion 6 extends out from the base and receives a slid able hub 11 of a treadle 12. 60 The hub has a square hole to shift onto the trunnion part 7 and effect a tipping of the shaft when the treadle is depressed. The treadle is readily shiftable sidewise onto and from the square part 7. 65

Superposed on the base 2 is a fire chamber unit chamber 15 converging upward and having a rim 16. Below the rim and extending forwardly of the chamber 15 there is a feed chute 17 inclining inward and 70 downwardly and having an open top or mouth.

A cover 18 resting on the lip of the mouth is hinged by rock-shaft 19 to a fixed part, here comprising a plate 20, having a standing, back flange 21 fastened by a strap 22 passing around the top or rim 16 of unit 15. A spring 23 on the rock-shaft 19 tends to lift the cover. 75

On rock-shaft 19 is fixed a lever 24 and 80 this is attached by link 25 to the treadle 12 in such relation that when the treadle is pressed downward the cover will be raised, thus leaving the hands of the person dumping in rubbish free and unneeded in opening the cover.

The treadle usually rests on the rounded part of trunnion 6, and is shifted to the square part 7 only when it is desired to dump the grate. 85

Fitted on top of the chamber 15 is an upwardly convergent hood unit 27 whose lower end is internally rebated at 28 to make a smoke proof lap and butt joint on the rim 16. The upper end of the hood has a neck 85 29 over which telescopes the flared foot of an extension chimney unit 30, one or more of which may be superimposed. The upper end of the unit 30 is reduced and provides a shoulder 31. 100

Mounted on the top of the unit 30 is a novel spark arrester comprising a head block or top 33 downwardly from which extends a set of bars 34 which are secured in a ring 35. Preferably the top 33 and the ring 35 105 are of concrete structure in which the ends of the bars 34 are embedded. A wire screen 36 surrounds the bars.

To prevent slamming down and breaking of the cover after it is opened I provide a 110

suitable check or bumper means. Preferably such means includes a pneumatic check cylinder 40 having a piston 41. In Fig. 3 the piston is shown as attached to link 25 so that on up movement of the link the piston moves up against compressed air in the cylinder, which is attached to the stationary plate 20. In Fig. 4 the piston is slidably mounted in the cover and is designed to strike the lip of the mouth of the chute 17, and be pressed back into its cylinder 40, on the lid or cover 18.

Another feature of the invention comprises a monolithic door block 42 to set into the draft hole 3. This block has a handle 43 engageable by a spring latch 44 which is attached to a cross-bar 45 connecting the ends of the base. Simply pushing the block 42 into the opening 3 causes it to latch; an outward pull quickly disengages it from the hook.

What is claimed is:

1. In an incinerator, a fire chamber having a forward and upwardly extending chute, and a cover on the top of the chute, a tipping

grate, and means for connecting the grate and the cover for coaction.

2. In a domestic incinerator, a fire chamber having a feed mouth closure, a tipping grate, and means for operating the closure and the grate concurrently.

3. In a domestic incinerator, a fire chamber having a feed mouth closure, a tipping grate, and means for operating the closure and the grate concurrently and for opening the closure independently of the grate.

4. In an incinerator, a fire chamber having a tiltable grate, a feed mouth cover means for tilting the grate and the cover, and a cushioning means controlling return of the grate and the cover.

5. In a domestic incinerator, a fire chamber having a feed mouth closure, a tipping grate, and means for operating the closure and the grate together and for independent action on the closure; said means including a grate rock-shaft and a lever shiftable from operative to ineffective position thereon.

JOSEPH FEIGENBAUM.
